(57) CLAIM

The ornamental design for a footwear cleaning device, as shown and described.

DESCRIPTION

FIG. 1 is a bottom perspective view of a footwear cleaning device showing my new design;

FIG. 2 is a top view thereof;

FIG. 3 is a bottom view thereof;

FIGS. 4 and 5 are first and second side views thereof;

FIGS. 6 and 7 are third and fourth side views thereof; and,

FIG. 8 is a top perspective view thereof.

In the drawings, the broken lines are shown for illustrative purposes only and form no portion of the claimed design.
